(57) **CLAIM**

The ornamental design for a pair of running shoes, as shown and described.

DESCRIPTION

FIG. 1 is a front perspective view of a pair of running shoes, showing my new design for a left shoe.

FIG. 2 is a rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

A right shoe of the pair of running shoes is a mirror image of the left shoe depicted in FIGS. 1 through 8.
